UNITED STATES PATENT OFFICE.

JEREMIAH HERRIN, OF WARSAW, INDIANA.

BASE FOR CHIMNEY-STACKS.

No. 843,813.

Specification of Letters Patent.

Patented Feb. 12, 1907.

Application filed February 5, 1906. Serial No. 299,563.

To all whom it may concern:

Be it known that I, JEREMIAH HERRIN, a citizen of the United States, residing at Warsaw, in the county of Kosciusko and State of Indiana, have invented a new and useful Base for Chimney-Stacks, of which the following is a specification.

The object of the present invention is to provide a base for chimney-stacks and to have the device adjustable to fit chimneys of different sizes, so as to partially close the open top thereof as well as to support a metallic stack. The device is made up of four duplicate sections capable of being conveniently assembled, so as to successively overlap and embrace the four corners of a chimney, there being fastenings for connecting the sections of the device after they have been properly adjusted to fit the chimney.

The particular advantage of the present invention resides in the fact that by having the device cast it will be strong and durable, and therefore outlast several sheet-metal stacks, it being necessary to replace the stack only when the latter has become burned out or otherwise damaged.

With these and other objects in view the present invention consists in the combination and arrangement of parts as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a perspective view showing a device of the present invention fitted to the top of a chimney and supporting a sheet-metal stack, the foot of the latter being broken away, so as to disclose all of the base. Fig. 2 is an enlarged fragmentary sectional view on the line 2-2 of Fig. 1. Fig. 3 is a cross-sectional view on the line 3-3 of Fig. 2. Fig. 4 is a detail perspective view of one of the duplicate sections of the device.

Like characters of reference designate corresponding parts in all of the figures of the drawings.

As hereinbefore indicated, the present device is made up of four duplicate sections, one of which has been shown in detail in Fig. 4 of the drawings, and is substantially L-shaped in form, including one relatively long flat member 1 and a shorter flat mem-

ber 2, set at right angles thereto. An upright flange 3 depends from the outer edge of each member of the section and terminates in an outwardly-flared lower portion 4. 60 From the inner edge of each member there rises an inwardly-bowed or arched hood portion 5, from the inner edge of which rises an upright flange 6, which inclines slightly inward. Upon the upper face of the member 2 65 and leading inwardly a suitable distance from its outer end is an upstruck socket 7, which is closed throughout its top and open at its bottom with openings 8 adjacent each end thereof. A boss 9 is provided upon the 70 upper face of the member 1, adjacent its outer end, and has a longitudinal slot 10.

In assembling the device preparatory to fitting the same to the top of a chimney, such as shown at 11 in Fig. 1 of the drawings, the four sections are brought together and successively overlapped, so as to form a rectangular cap, with the boss 9 of each section received within the socket 7 of the adjacent section, the slot of each boss being registered with one of the openings 8 of the adjacent socket. A bolt 12 is passed downwardly through each slot 10 and the adjacent opening 8, and a nut 13 is fitted to the lower end of the bolt and received within the 85 hollow boss 9. It will here be explained that the cap-sections are merely loosely connected prior to being fitted to the chimney, and after the sections have been snugly embraced upon the top of the chimney the 90 screws are tightened by means of a screwdriver, as the nuts 13 are held against rotation in the bosses 9 and rest upon the top of the chimney. Additional security may be given to the cap by means of mortar or cement applied to the top of the chimney prior to fitting the cap thereto, or mortar or cement may be placed in the annular recess formed between the walls of the chimney and the flared portion 4 of the flange 3. After the 100 cap has been fitted to the chimney the metallic stack 14 is set down around the 105 standing flange 6, with its bottom resting upon the hood 5, and suitable guys (not shown) may be employed to brace the stack.

From the foregoing description it will be understood that the device of the present invention is to be cast in four duplicate sections, which are proportioned so as to successively overlap when assembled and capable of being adjusted, so as to fit the standard sizes of chimneys. By having the cap

separate from the sheet-metal stack the latter may be replaced several times without the necessity of replacing the cap.

Having thus described the invention, what is claimed is—

1. A device of the character described comprising complementary sections each provided with a hood portion capable of being adjustably overlapped when assembled 10 and adapted to partially close the open end of a chimney and form a support for a chimney-stack, each section being provided at its outer edge with a depending flange and at its inner edge with an upstanding flange, and 15 fastenings to connect the overlapped portions of the sections.
2. A device of the character described comprising four duplicate corner-sections capable of being adjustably overlapped when 20 assembled and each provided with an inwardly-extending hood adapted to partially close the open end of a chimney and form a support for a chimney-stack, said sections being provided at their outer edges with depending flanges and at their inner edges with upstanding flanges, one of said sections being provided with an upstruck perforated socket and the mating section with a slotted boss 25 adapted to engage said socket, and fastening devices extending through the perforations and slots of the several sections.
3. A device of the character described comprising duplicate sections capable of being adjustably overlapped when assembled, 30 each section being provided with a depending flange at its outer edge, an arched flange at its inner edge, an upstanding flange at the free edge of the arched flange, and fastenings to adjustably connect the overlapped portions of the sections.
4. A device of the character described comprising adjustable overlapped sections each provided with a hood portion adapted to partially close the open end of a chimney 40 and form a support for a chimney-stack, one section having a socket, which is open in its under side and pierced by an opening, the adjacent overlapped section having an up-

standing hollow boss to fit within the socket and provided with a slot for registration with the opening of the socket, and a fastening to extend through the slot and the opening.

5. A device of the character described comprising a series of duplicate corner-sections each provided with a hood portion adapted to partially close the open end of a chimney and form a support for a chimney-stack, one member of each corner-section having a longitudinal slot open throughout its under side and provided with an opening through its back, the other member of the section having an upstanding hollow boss open throughout its under side and provided with a longitudinal slot, the boss of each section being adapted to adjustably fit within the socket of the adjacent overlapping section, and fastenings to pass through the openings of the sockets and the slots of the bosses.

6. A device of the character described comprising four duplicate corner-sections each section including a substantially L-shaped body having a depending flange throughout its outer edge, an arched flange rising from the inner edge of the body, and an upstanding flange at the free edge of the arched flange, one body member of each section being provided with an upstanding socket leading inwardly from one end and open throughout its under side with openings adjacent its ends, the other body member having an upstanding boss open throughout its under side and provided with a longitudinal slot, the bosses being adjustably received within the successive sockets when the sections are assembled, bolts passing through the openings of the sockets and the slots of the bosses, and nuts fitted to the bolts and received within the bosses.

In testimony that I claim the foregoing as my own I have hereto affixed my signature in the presence of two witnesses.

JEREMIAH HERRIN.
